COIL SPRING METATARSAL ARCH SUPPORT

Filed Feb. 3, 1930

FIG.1.

FIG.2.

FIG.3.

INVENTOR.

William Seigle
BY Loyd J. Miller

ATTORNEY.

UNITED STATES PATENT OFFICE

WILLIAM SEIGLE, OF HINTON, OKLAHOMA

COIL SPRING METATARSAL ARCH SUPPORT

Application filed February 3, 1930. Serial No. 425,669.

My invention relates to supports for the metatarsal arch of the human foot.

This invention is an improvement over a coil spring metatarsal arch support for which 5 application for patent was filed by me on April 19, 1929, under Serial Number 356,521, for which Patent No. 1,763,260 was granted June 10, 1930. I do not wish to claim as new 10 anything herein which was covered in the above referred to application. The objects of my invention are to provide a base for the above mentioned support and to provide certain modifications in the construction of the device in order to apply it to the base; to 15 provide a support which will be new, novel, practical and of utility; which may be simply and quickly attached within a shoe; which will permit the easy and quick removal of the support from the shoe without the removal 20 of the base; which will be cheap in manufacture; which will be durable; and which will be efficient in accomplishing all the purposes for which it is intended.

With these and other objects in view as 25 will more fully appear, my invention consists in the construction, novel features, and combination of parts hereinafter more fully described, pointed out in the claims hereto appended, and illustrated in the accompanying 30 one-sheet drawings, of which,

Figure 1 is a plan view of the device positioned upon a fragment of a shoe sole;

Fig. 2 is an enlarged plan view of the spring attached to a fragment of the base; 35 and

Fig. 3 is an elevational sectional view of the device disposed upon a fragment of shoe sole.

Like characters of reference designate like 40 parts in all the figures.

It is understood that various changes in the form, proportion, size, shape, weight and other details of construction, within the scope 45 of my invention may be resorted to without departing from the spirit or broad principle of my invention and without sacrificing any of the advantages thereof; and it is also understood that the drawings are to be interpreted as being illustrative and not restrictive.

One practical embodiment of the invention as illustrated in the drawings follows:

A base 1, having beveled or skived edges 2, and a perforation 3 adjacent its rear central portion. Said base 1 is made of some soft 55 fibrous material such as felt or the like, and is adapted to be glued or fastened as shown at 4 upon the top surface of a shoe sole 10 or adjacent a point where the metatarsal arch of a human foot normally rests. The entire 60 central portion of said base 1 is slightly depressed as shown at 5 for receiving the largest and lowermost loop 6 of a conical coil spring 7. Said depression 5 is shaped to conform to the shape of said coil 6. Two sides 65 of said loop 6 are connected by a flat metal strip 8, the office of which is pertinent to this application only in that it confines said loop 6 from spreading when any weight is applied upon the top coils of said spring 7. Said loop 6 terminates in a free end 9 slightly 70 past the portion of the loop which lies nearest the heel of the shoe. Said spring 7 is covered by a cap 11 preferably made of 75 rubber or other semi-resilient material.

In installing the support in a shoe, the base 1 will be glued or otherwise fastened to the sole at a desired point. The end 9 of said spring 7 will be inserted through said perforation 3 and the spring turned to a position as best shown in Fig. 3. This will force said end 9 under the base 1 and on top of the shoe sole 10. The largest coil 6 will snugly seat in said depression 5 and be held therein by the portion of loop 6 which is lying beneath base 1. The manner of removing said 80 spring 7 will be obvious.

Obviously, the invention is susceptible of embodiment in forms other than that which is illustrated in the accompanying drawings 85 and described herein, and applicable, for uses and purposes other than as detailed, and I therefore consider as my own all such modifications and adaptations and other uses of the form of the device herein described as 90 fairly fall within the scope of my invention.

Having thus described my invention, what is claimed and desired to be secured by Letters Patent, is:

1. The combination with a coil spring met- 100

atarsal arch support having a conical coil spring for supporting the metatarsal arch of a human foot, of a flat fibrous base adapted to be attached to the top surface of a shoe sole, said base having skived edges and having a perforation in its rear central portion for receiving the free end portion of the lower loop of said spring.

5 2. Organization as described in claim 1, in which the entire central portion of the upper surface of said base is depressed to conform to the shape of and snugly fit the lower loop of said spring.

10 3. The combination with a metatarsal arch support having a conical coil spring for supporting the metatarsal arch of a human foot, of a lower loop of said spring having its end portion bent slightly downward, a flat fibrous base adapted to be attached to the top surface of a shoe sole, said base having skived edges and having a perforation through its rear central portion for receiving the bent end portion of said spring.

15 4. Organization as described in claim 3 in which the entire central portion of the upper surface of said base is depressed to conform to the shape of and snugly fit the lower loop of said spring.

20 WILLIAM SEIGLE.
